United States Patent Office

Des. 207,074
Patented Feb. 28, 1967

207,074

SAFETY REFLECTOR

Morris Rider, 436 W. Grand Blvd.,
Detroit, Mich. 48216

Filed May 31, 1966, Ser. No. 2,488

Term of patent 14 years

(Cl. D72—1)

FIG. 1

FIG. 3

FIG. 2

FIG. 4

FIG. 5

FIG. 1 is a front elevational view of a safety reflector illustrating my new design;

FIG. 2 is a rear elevational view thereof;

FIG. 3 is a right side view thereof, the left side being a mirror image of the right side shown.

FIG. 4 is a top view thereof; and,

FIG. 5 is a bottom view thereof.

I claim:

The ornamental design for a safety reflector, substantially as shown and described.
